ABSTRACT OF THE DISCLOSURE

A sundial comprising a base adapted to be vertically disposed and having an inclined mounting surface, a pivot mounted on such surface and an arcuate dial plate rotatably mounted on the pivot. A style plate is mounted at an angle to the surface and has two parallel shadow casting edges, one for before noon and the other for afternoon, spaced by a selected distance so that the shadow of an edge upon the arcuate dial plate can indicate time. The arcuate dial plate has approximately equally spaced hour-marks graduated on a fixed radius from the pivot. A "location" correction scale is fixed to the surface adjacent to the edge of the arcuate dial plate. The dial plate has "season" correction reference indicia for selectively setting the dial plate with respect to the "location" correction scale.

This invention relates to an improvement in south facing vertical sundials. The sundial of the present invention has a semicircular, nearly equally graduated dial and a very thick gnomon, which has two parallel styles widely spaced apart from each other. The graduation plate can be shifted around its center for the purpose of eliminating errors, depending on observer's location and the season. The shadow of the style on the dial tells standard time directly.

In the following figures, same reference numbers designate same components in all the figures.

BRIEF DESCRIPTION OF THE DRAWINGS

FIG. 1 is a theoretical illustration of the graduations of the dial of this invention;

FIG. 2 is a front view of the sundial of this invention;

FIG. 3 is a perspective view of the dial in use showing the shadow indicating 10:30 a.m.,

FIG. 4 is a side view of the dial partly in section through the dial pivot and a clearance hole in the dial.

The following explanation and FIG. 1 show an accurate method of laying out the hour marks for the new sundial. In FIG. 1, the lines O-12, O-11, O-10, O-9 . . . which have been used from ancient times, are the morning hour lines for ordinary south vertical sundials in the latitude β° . β can vary within a wide range, but now, for convenience, the explanations will be made here for $\beta=45^{\circ}$.

The hour graduation angle a_i is computed by the following formula

$$\tan a_i = \cos 45^{\circ} \tan t_i \quad (1)$$

where t_i is the sun's hour angle. The plotted values of a_i are as follows:

TABLE 1

	Diff.
$a_{12}=0^{\circ}0'$	
$a_{11}=10^{\circ}43.7'$	$10^{\circ}43.7'$
$a_{10}=22^{\circ}12.5'$	$11^{\circ}28.8'$
$a_9=35^{\circ}15.9'$	$13^{\circ}3.4'$
$a_8=50^{\circ}46.1'$	$15^{\circ}30.2'$
$a_7=69^{\circ}14.8'$	$18^{\circ}28.7'$
$a_6=90^{\circ}0'$	$20^{\circ}45.2'$

2

These hour lines, shown in Table 1 and FIG. 1, have unequal intervals. The invention contemplates a new method of laying out the hour marks M, P, Q, R, S, T and U which have nearly equal intervals. As in FIG. 1, draw the line 60B from point 6 to a point B through O and draw the line BAF perpendicular to 60B from B. Draw the arc UM with radius l and center pivot at A. The arc UM cuts the hour lines O-6, O-7, O-8, O-9, O-10, O-11 and O-12 at U, T, S, R, Q, P and M respectively.

And then

$\angle FAM=\theta_{12}$, $\angle FAP=\theta_{11}$, $\angle FAQ=\theta_{10}$, $\angle FAR=\theta_9$ . . . θ_i : i is generic and indicates the hour.

FIG. 1 shows the relation between a_9 and θ_9 . When a line is drawn perpendicular to OR, the 9 o'clock line, at J from the center A.

$AO=m$, $\angle AOB=\alpha$
 $AM=AP=AQ=AR \dots =l$: Radius of the arc

$\angle MOP=\theta_{11}$, $\angle MOQ=\theta_{10}$, $\angle MOR=\theta_9$ . . .
 $\angle FAM=\theta_{12}$, $\angle FAP=\theta_{11}$, $\angle FAQ=\theta_{10}$, $\angle FAR=\theta_9$ . . .

Then

$$m \cos (a_9 - \alpha) = l \sin (\theta_9 - a_9) = AJ$$

In general:

$$m \cos (a_i - \alpha) = l \sin (\theta_i - a_i) \quad (2)$$

By the trial and error method, from Formulas 1 and 2, θ_i values were computed which have nearly arithmetically progressive values.

When $OB=7.50$ cm., $BA=3.75$ cm., $l=16.77$ cm., θ_i has nearly equal differences as in Table 2.

TABLE 2

	Diff.
$\theta_{12}=26^{\circ}33.9'$	
$\theta_{11}=39^{\circ}28.8'$	$12^{\circ}54.9'$
$\theta_{10}=52^{\circ}6.8'$	$12^{\circ}38.0'$
$\theta_9=64^{\circ}53.1'$	$12^{\circ}46.3'$
$\theta_8=77^{\circ}54.0'$	$13^{\circ}0.9'$
$\theta_7=90^{\circ}48.7'$	$12^{\circ}54.7'$
$\theta_6=102^{\circ}55.3'$	$*(12^{\circ}6.6')$

*Mean value $12^{\circ}51'$ except $12^{\circ}5.5'$.

From Table 2 the differences between the angle of θ_i , namely $12^{\circ}54.9'$, $12^{\circ}38.0'$, $12^{\circ}46.3'$, $13^{\circ}0.9'$ and $12^{\circ}54.7'$ are almost equal to one another except $12^{\circ}6.6'$ (graduations from 6 to 7 a.m. are of little importance because they are used for a very short period), and the means value is $12^{\circ}51'$. The maximum deviation from the mean value is $13'$ and the ratio of the error to the mean value is less than 1.7%. For instance, when the difference between the solar time and the standard time is 25 minutes, the dial plate is shifted by an angle corresponding to 25 minutes around A; then the shadow of the style tells directly the standard time within an error less than about 25 seconds (25 minutes $\times$ 1.7%). This error originates in the non-uniformity of the graduation. The extent of this error is permissible.

Therefore when a south facing vertical sundial is used in the latitude 45° N, it is very convenient to use the hour mark points M, P, Q, R . . . instead of hour lines O-12, O-11, O-10, O-9 . . . These hour points M, P, Q, R . . . tell us 12, 11, 10, 9 . . . o'clock respectively.

Graduation for afternoon hours is made symmetrically to the line BAF on the right part of the dial plate 1 in FIG. 2 and FIG. 3.

In FIG. 2, the small graduation 12, attached to the dial plate 1, is a "season" correction scale for the correction according to the equation of time (apparent time-mean time). The graduation 13, fixed on the base 4, is for the correction according to the observer's location. These two graduations are divided by the mean value of the dial graduation.

The scales of **12** and **13** are graduated in such a way that one division of graduation **12** corresponds to 4 minutes in time of the "season" correction and that of graduation **13** corresponds to 1° of the "location" correction. Then, the angular distance around center A between two neighbouring graduations becomes $51.4'$.
5

With the aid of these two scales, the dial plate can be easily and quickly adjusted for the standard time.

FIG. 3 diagrammatically shows the dial when in use. The style plate **2** at OXX'O' always makes an angle of 45° 10 with the dial plate **1**, because the graduation is for a south facing vertical sundial in the latitude 45° N.

As illustrative of other settings when the sundial is in the latitude ψ , suppose $\psi=35^\circ$ N.

In FIG. 3, OO' is set parallel to the east-west horizontal line. The line OO' cuts the graduation at 6 a.m. and 6 p.m. hour marks. A semicircular dial plate **1** of this sundial faces due south, and makes an angle with vertical line **5** equal to 10° . Thus two edges OX and O'X' of the style **2** points to the celestial pole. OY, the shadow 20 of OX, tells the solar time half past 10 o'clock a.m. and in the afternoon the shadow of O'X' on the right part of the dial tells the afternoon solar time in the same way.

In FIG. 2, graduation **13** is provided for places in Japan, near the longitude 135° E. For instance, when the "season" correction is +8 minutes at a place of longitude 140° E, near Tokyo, the main dial plate must be shifted around the center A to the position where the +8 minutes line in graduation **12** coincides with the 140° E line in graduation **13**. Then the shadow of the style of the gnomon on the dial plate tells us the standard time in longitude 135° E, which is the Japanese Standard Time meridian.

As seen in FIG. 4, base **3** supports the dial, and surface **4** makes an angle with the vertical line equal to 10° 35 ($45^\circ - \psi = 10^\circ$ when $\psi=35^\circ$ N).

Side boards **15** and **16** and props **14** support the roof-like style plate.

The pivot A of the graduation arc, used to correct errors depending on the observer's location and the season, is under the roof-like style plate of the gnomon and protected from nature.

As seen in FIG. 2 and FIG. 3, slots **7** and **9** are the guide grooves of the dial plate **1**, and after correcting the errors, the dial plate is fixed by set screws **6** and **8**. Apertures **10** and **11** are the windows or holes which allow the dial plate to rotate freely irrespective of the props **14** of the style plate **2**.

If the correction is made on this dial, the dial can directly tell standard time very accurately between about 7 a.m. and 5 p.m., while the sun shines upon the dial.

The error of the time, which the sundial shows, is negligibly small.

I claim:

1. A sundial comprising a base adapted to be vertically disposed and having an inclined mounting surface, a pivot mounted on said surface, an arcuate dial plate rotatably mounted on said pivot, a style plate mounted at an angle to said surface and having two parallel shadow casting edges, one for before noon and the other for afternoon, spaced by a selected distance so that the shadow of an edge upon said arcuate dial plate can indicate time, said arcuate dial plate having approximately equally spaced hour-marks graduated on a fixed radius from said point, and a "location" correction scale fixed to said surface adjacent to the edge of said arcuate dial plate, said dial plate having "season" correction reference indicia for selectively setting said dial plate with respect to said "location" correction scale.

2. A sundial as claimed in claim 1 in which a selected angular displacement of said dial plate around said pivot corresponds to a same time interval on the "season" correction indicia, and the "location" correction scale.
